CLAIM

The ornamental design for a central console for automobile as shown and described.

DESCRIPTION

FIG. 1 is a front, top, left side perspective view of a central console for automobile showing our new design;

FIG. 2 is a front, top, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The lightened part of the photograph shown in a coarser pattern filter within the broken line perimeter, illustrates portions of the central console for automobile that forms no part of the claimed design. The broken lines form no part of the claimed design.

1 Claim, 8 Drawing Sheets
